UNITED STATES PATENT OFFICE.

GEORGE E. WEBB, OF MILWAUKEE, WISCONSIN, ASSIGNOR TO HOERRING COMPANY, OF MILWAUKEE, WISCONSIN, A CORPORATION.

SUBGRADE PLANER.

Application filed January 6, 1922. Serial No. 527,423.

To all whom it may concern:

Be it known that I, GEORGE E. WEBB, citizen of the United States, residing at Milwaukee, in the county of Milwaukee and

5 State of Wisconsin, have invented certain new and useful Improvements in Subgrade Planers, of which the following is a specification.

The present invention relates to a device 10 for planing and finishing the subgrade of a road, pavement or the like, preparatory to depositing the concrete or other road building material upon the subgrade.

In the building of roads under present 15 day methods a portable self-propelled road building machine is ordinarily employed for mixing the ingredients and depositing them upon the subgrade, the machine being adapted to travel over the subgrade as the 20 building of the road progresses. The surface of the subgrade as it is originally formed is quite frequently cut up and disturbed by the necessary transportation of material from the source of supply to the 25 road building machine, and the subgrade planer of the present invention is adapted to be moved over the subgrade to remove any disturbances or unevenness from the 30 surface thereof just before the concrete or road building material is deposited in position.

The subgrade planer can be operatively associated with the road building machine so as to be propelled or advanced thereby as 35 the road building progresses, and the construction of the planer is such that it does not interfere in any manner with the normal operation of any of the parts of the road building machine.

40 Two of many possible embodiments of the invention are illustrated by the accompanying drawings in which:

Figure 1 is a side elevation of the rear 45 end of a conventional concrete paving machine, showing the subgrade planer as operatively associated therewith.

Figure 2 is a top plan view of the subgrade planer and fragmentary portions of the rear multiplane tractors upon which the 50 paving machine is mounted.

Figure 3 is a view of one end of the device illustrating more clearly the means for adjusting the elevation of the scrapers.

Figure 4 is a fragmentary side elevation

of the rear end of a conventional concrete 55 paving machine, showing a modified form of subgrade finishing device operatively associated therewith.

Figure 5 is a top plan view of the modified form of subgrade finishing device, the 60 endless track laying tractors and front axle of the paving machine being shown in a diagrammatic manner for the purpose of illustrating the manner of attaching the device of the invention to the paver. 65

Figure 6 is an enlarged transverse sectional view through the subgrade finisher or planer of Figure 5.

Figure 7 is a rear view of the modified form of subgrade finisher. 70

Figure 8 is an enlarged detail view of a portion of the forward scraper and the scarifying teeth which are associated therewith in the modified construction.

Corresponding and like parts are referred to in the following description and illustrated in all of the views of the drawings by like reference characters. 75

The subgrade planer or finisher of the present invention is adapted to be used in association with a road making machine and, for the purpose of illustration, it is shown on the drawings as adapted to be arranged at either the front or the rear end of a conventional paving machine so that it is shoved 80 or pushed along the subgrade as the paving operation progresses and the paver is advanced. These pavers, as is well known in the art, comprise a power driven concrete mixer and means for charging the necessary 85 ingredients into the mixer and also means for depositing the mixed concrete in proper position upon the subgrade. The paver is designated as a unit by the reference character A and only fragmentary portions 90 thereof are shown. The usual loading skip 1 is shown by Figure 1 in a lowered position, and the endless tread or multiplane tractors which are adapted to be driven by the power unit of the paving machine so 95 that the said machine is self-propelled are indicated at 2. The subgrade planer is indicated as a unit by the reference character B and is shown as located adjacent either the front end or the rear end of the paver A so 100 as to be shoved or pushed along by the paver as the said paver is advanced. The planer B is adapted to be mounted upon the usual

road form rails C which are set to the grade of the road and serve to hold the scraping or scarifying elements of the planer at the proper elevation.

5 Specifically describing the embodiment of the invention illustrated by Figures 1 to 3 of the drawings, the frame of the subgrade planer B extends transversely across the sub-grade of the road and may be formed in any 10 suitable manner, being indicated as fabricated in a conventional manner from ordinary structural steel units. The ends of the frame are formed with extensions 3 and this arrangement is advantageous in that it provides a clearance space for the loading skip 1 of the paver between the said extensions.

The ends of the frame are movably supported by flanged rollers 4 and sliders or sliding shoes 5 which engage the road rails C and are adapted to travel thereon. In the specific construction illustrated, each of the extensions 3 of the frame carries a flanged wheel or roller 4 and the opposite corner of the frame is provided with one of the sliding shoes 5. In order to hold the frame against lateral displacement, a horizontally disposed roller 6 is arranged at each end thereof, said roller being arranged to engage the inner faces of the road rails. The frame is thus mounted so that it can move freely along the road rails although it is held against lateral displacement thereon.

Mounted upon the two ends of the frame 20 are the diagonal scrapers 7 which extend forwardly along the end extensions 3 and converge rearwardly toward the middle of the machine and the road bed. The middle portion of the subgrader frame is provided with a pair of shorter scrapers 8 which are reversely inclined and form a V with the point thereof facing forwardly at substantially the middle portion of the frame. The rear ends of the longer scrapers 7 extend beyond the ends of the shorter scrapers 8 in a spaced relation thereto so that any material which is not deposited in depressions will be left behind the planer in two rows. This material can be removed or otherwise handled in the most expedient manner. The operating edges of the scrapers are preferably inclined or curved forwardly as indicated quite clearly by Figures 2 and 3 of the drawings, so that they will act in an effective manner upon the surface of the subgrade to remove any unevenness thereof, those portions of the subgrade which are above the proper elevation being scraped or planed away and the loose material deposited in the depressions or left in rows behind the device.

Means is preferably provided for raising and lowering the scraper or scarifying elements so that they can be set at different elevations. For this purpose, as is indicated

by Figure 3, the flanged rollers 4 may be carried by arms 9 which are pivoted at 10 to the ends of the frame, the swinging ends of the arms being engaged by screws 11 which are carried by the frame of the device. The screws are shown as provided with suitable handles 12 and it will be obvious that by an appropriate manipulation of these screws, the forward end of the frame can be raised or lowered to set the corresponding ends of the scrapers of scarifiers at different elevations. A nicely of adjustment is thus possible to adapt the device for the most effective operation under different conditions of service.

The rear edge of the frame, or that edge of the frame which is adjacent the paving machine is provided with a series of horizontally disposed rollers 13 which are arranged in such a manner as to be engaged by a thrust or bumper bar 14 which is carried by the front end of the paver. This bar 14 is secured to the paver in some suitable manner as by means of the braces 15 and is of a sufficient length to engage a plurality of the rollers 13 at one time. The ends of the thrust bar or bumper 14 are preferably curved, as indicated at 14a so that the bar can travel laterally on the rollers 13. As the paver is advanced, the thrust bar or bumper 14 acts upon the subgrade planer or finishing device B to push the same along upon the road rails C, and the relation between the paving machine and subgrade planer is such that the paving machine can be shifted laterally relative to the subgrade planer and positioned upon either side of the subgrade or at the center thereof, as may be necessary to get the most effective results. The construction of the frame is such as to provide a clearance space between the extensions 3 at the ends thereof so that there is no interference with the normal operation of the loading skip 1 of the paver, and the planer is advanced with the paving machine so as to finally scrape and smooth the surface of the subgrade and place it in proper condition to receive the concrete or road building material.

The bumper bar 14 may be secured to the frame of the paver in any suitable manner and, as shown by Figure 2, it has a pin and slot connection 15 with the braces 15 so that it is susceptible of being shifted longitudinally. It may either be tightly clamped in an adjusted position or permitted to have a loose engagement with the braces 15 so that it can shift freely back and forth. This manner of mounting the bumper bar enables it to be made sufficiently long to engage quite a number of the rollers 13 and the frame is thereby maintained in a proper position substantially normal to the road bed as it is propelled along the road rails, and there is little or no tendency for the

frame to be pushed into an angular or skewed position.

A modified form of the invention is illustrated by Figures 4 to 8 of the drawings. 5 This form of the subgrade planer is associated with the opposite end of the paver. In Figure 4 the rear end of the paver is shown in a fragmentary manner, and the distributing means is of the boom and bucket 10 type, the boom being designated by the numeral 1^a and the bucket by the numeral 2^a. The multiplane tractors of the paver are indicated at 2, and the axle which connects the tractors is indicated at 2^b. 15 The modified form of subgrade finisher, which, as in the previous instance, is designated as a unit by the reference character B is operatively associated with the paver so as to be propelled or advanced thereby, 20 being shown as having a connection with the axle 2^b and being located adjacent the tractors 2. In this position the subgrade finisher is located between the inner-most position of the distributing bucket 2^a and the tractors 2 so that it does not interfere in any 25 manner with the movements of the bucket along the boom or prevent the mixed concrete batches from being deposited upon the subgrade at any point in the travel of the bucket upon the boom.

The frame of this form of subgrade finisher includes spaced and substantially parallel transverse beams 21 and 22 which are connected at intervals in their length by the 30 cross pieces 23. The ends of the frame are each provided with a pair of flanged rollers 24 which are adapted to travel upon the usual road rails or forms C. Horizontally disposed rollers 24^a are also shown as arranged at the ends of the frame for engagement with the road rails C to assist in holding the frame against lateral displacement. 40 A transversely extending scraper 25 is secured to the cross pieces 23 at a point somewhat to the rear of the front transverse beam 21, and a channel bar 25^a is shown as associated with the horizontally disposed and rearwardly extending upper edge portion of the scraper to stiffen and reinforce the 45 same. This scraper 25 extends downwardly so as to engage the surface of the subgrade and is forwardly inclined so that it can act effectively upon any elevations of the subgrade to plane or cut the same away. Associated with the front scraper 25 is a series 50 of teeth 26, said teeth being shown as secured thereto and extending downwardly along the front thereof. The purpose of these teeth is to assist in breaking up or 55 rooting up the hard spots in the surface of the subgrade so that the device will operate effectively to remove any high places in the subgrade. The loosened earth may be deposited in low places so as to fill the same, 60 or, if it accumulates in sufficient quantities

in front of the scraper 25 it will press over the top edge of the scraper and drop upon the subgrade at the rear of the scraper. The space between the front scraper 25 and the front beam 21 is sufficient to permit of this 70 passage of the loosened earth over the top of the front scraper in the manner indicated.

The rear beam 22 of the frame is provided with a rear scraper 27 which is shown as disposed in a substantially vertical position. 75 This scraper projects downwardly into engagement with the surface of the subgrade and cooperates with the front scraper to smooth out the uneven places. Any raised points which may not have been all removed by the front scraper will be planed away by the rear scraper and the loose earth accumulating in front of the rear scraper will be deposited in the low places so as to fill in the same. If an excessive quantity of 80 loose earth should accumulate in front of the rear scraper, it would pass over the same, in which event it would have to be manually removed from the subgrade, 85 although this is a contingency which would not ordinarily happen if the preliminary work of grading had been properly done. Under some conditions it might be necessary for a workman to shovel some loose earth between the two scrapers in order to 90 provide sufficient material for filling in the depressions.

The connection between the subgrade finisher and the paving machine is such that it is possible to alter the relative position of the two devices and position the paving machine at either side of the center of the road, as may be necessary to obtain the most effective results. A yoke member 28 is slidably associated with the axle 2^b of the traction devices 2 of the paver and carries a wheel 29 which is adapted to travel back and forth upon the axle in much the manner of a trolley. The yoke 28 is connected by a pair of rearwardly diverging draw bars 30 to the frame of the subgrade finisher. The connection is such that the finisher is pulled along after the paver and propelled thereby, although the paver can be shifted laterally with respect to the finishing machine and positioned upon one side of the road or the other side, as may be desired. The subgrade is finished and smoothed after the paver has passed over the same so that it is put in proper condition to receive the concrete just before the concrete is deposited thereon, and this is accomplished without interfering in any manner with the functioning of any part of the paver.

As is indicated more clearly by Figure 8, both the front and rear scrapers may be formed so that they can be adjusted for different contours or configurations of the subgrade surface. As indicated, the rear scraper 27 is shown as formed in a plurality

of sections which are adjustably secured to the rear beam 22 by fastening elements 31. By properly adjusting the scraper sections, the scrapers can be positioned at different elevations and also set for the desired contour of the subgrade surface.

While I have described two particular embodiments of the invention, it will be understood that numerous modifications and changes can be made in the details of construction without departing from the spirit of the invention and all within the scope of the claims.

Having thus described my invention, what I claim as new and desire to secure by Letters Patent, is:

1. In combination, a portable road building machine, a movably mounted subgrade finisher extending over the subgrade and disconnected from the road building machine, and a pusher element carried by the road building machine and adapted to engage the finisher at a point in the length thereof to shove the finisher forward as the road building machine is advanced.

2. The combination with a portable road building machine, and the usual road rails, of a finisher disconnected from the road building machine and extending across the subgrade and mounted to travel upon the road rails, means cooperating with the road rails to hold the finisher against lateral displacement, and a pusher bar carried by the road building machine and adapted to engage an intermediate point of the finisher to advance the same along the road rails.

3. The combination with a portable road building machine, a subgrade finisher mounted to move over the subgrade, means for holding the subgrade finisher against lateral displacement, a transverse series of anti-friction elements upon the finisher, and a pusher bar carried by the road building machine and engaging the anti-friction elements to move the finisher as the road building machine is advanced, the road building machine being shiftable laterally with respect to the finisher.

4. The combination with a paving machine having a loading skip at one end thereof, of a subgrade finisher including a frame arranged at the end of the paver having the loading skip, the said frame being constructed to provide a clearance space for the loading skip, and subgrade finishing elements carried by the frame.

5. The combination with a road building machine having an operating member projecting from one end thereof, and a subgrade finisher frame extending across the subgrade and arranged adjacent the said end of the road building machine, said frame having extensions at opposite ends thereof which are arranged laterally beyond the zone of operation of the projecting mem-

ber of the road building machine, and subgrade finishing elements carried by the frame and its extensions.

6. The combination with a road building machine having an operating member projecting from one end thereof, of a subgrade finisher frame extending across the subgrade adjacent the said end of the road building machine and having longitudinal extensions at the ends thereof which are laterally spaced from the zone of operation of the projecting member of the road building machine and define a clearance space for the said member between the same, subgrade finishing elements carried by the frame and its extensions, and means whereby the frame is advanced with the road building machine.

7. A subgrade finishing device including a frame mounted to travel upon the usual road rails, and a scraper carried by the frame, said scraper being adjustable for different contours of subgrade surface.

8. A subgrade finishing device including a frame mounted to travel over the subgrade, and a pair of spaced scraping elements carried by the frame and arranged in a position transverse to the direction of movement thereof whereby material accumulating between the scrapers will be deposited in the hollows or depressions of the road bed.

9. A subgrade finishing device including a frame mounted to travel over the subgrade, a pair of spaced scraping elements carried by the frame and the rear scraping element being arranged in a position transverse to the direction of movement of the frame, and scarifying teeth associated with the forward scraping element whereby elevations will be cut away by the forward scraper and the loose material deposited in the hollows by the rear scraper.

10. A subgrade finishing machine including a frame mounted to travel over the subgrade, a pair of spaced scraping elements carried by the frame and arranged in a position transverse to the direction of movement thereof, the forward scraper being inclined so that loose material will pass over the same and accumulate in the space between the scraping elements where it will be deposited in the hollows by the rear scraping elements.

11. A subgrade finishing machine including a frame mounted to travel over the subgrade, a pair of spaced scraping elements carried by the frame and arranged in a position transverse to the direction of movement thereof, the forward scraper being inclined so that loose material will pass over the same and accumulate in the space between the scraping elements where it will be deposited in the hollows by the rear scraping elements, and scarifying means associated with the front scraper.

12. In combination, a portable road building machine, a movably mounted subgrade finisher extending over the subgrade and disconnected from the road building machine, and a pusher element adjustably mounted upon the road building machine and adapted to engage the finisher at different points in the length thereof to advance the finisher as the road building machine is moved.

13. The combination with a portable road building machine, of a movably mounted

subgrade finisher extending over the subgrade, a transverse pusher bar mounted upon the road building machine and slidably 15 thereon in a direction transverse to the direction of movement of the road building machine, and means upon the finishing machine for engagement with the pusher bar in any possible position thereof for causing 20 the finisher to advance as the road building machine is advanced.

In testimony whereof I affix my signature.

GEORGE E. WEBB.

12. In combination, a portable road building machine, a movably mounted subgrade finisher extending over the subgrade and disconnected from the road building machine, and a pusher element adjustably mounted upon the road building machine and adapted to engage the finisher at different points in the length thereof to advance the finisher as the road building machine is moved.

13. The combination with a portable road building machine, of a movably mounted

subgrade finisher extending over the subgrade, a transverse pusher bar mounted upon the road building machine and slidably 15 thereon in a direction transverse to the direction of movement of the road building machine, and means upon the finishing machine for engagement with the pusher bar in any possible position thereof for causing 20 the finisher to advance as the road building machine is advanced.

In testimony whereof I affix my signature.
GEORGE E. WEBB.

Certificate of Correction.

It is hereby certified that in Letters Patent No. 1,534,046, granted April 21, 1925, upon the application of George E. Webb, of Milwaukee, Wisconsin, for an improvement in "Subgrade Planers," errors appear in the printed specification requiring correction as follows: Page 4, strike out lines 83 to 130, comprising claims 7, 8, 9, 10, and 11; page 5, line 1, for claim "12" read 7, and line 11 for claim "13" read 8; and that the said Letters Patent should be read with these corrections therein that the same may conform to the record of the case in the Patent Office.

Signed and sealed this 31st day of August, A. D. 1926.

[SEAL.]

M. J. MOORE,
Acting Commissioner of Patents.
